DESIGN FOR A HAND GAFF

George R. O'Brien, Superior, Wis., assignor of one-half to Charles De Frehn, Superior, Wis.

Application April 24, 1939, Serial No. 84,534

Term of patent 7 years

To all whom it may concern:

Be it known that I, George R. O'Brien, a citizen of the United States and a resident of Superior, in the county of Douglas and State of Wisconsin, have invented a new, original, and ornamental Design for a Hand Gaff, of which the following is a specification, reference being had to the accompanying drawing, forming part thereof.

In the drawing:

I claim:

The ornamental design for a hand gaff, as shown.

GEORGE R. O'BRIEN,
